DEMONSTRATION BOOTH

Rene D. Wasserman, New York, N. Y.

Application January 13, 1949, Serial No. 224

Term of patent 7 years

(Cl. D80—9)

To all whom it may concern:

Be it known that I, Rene D. Wasserman, a citizen of Switzerland, residing at New York city, in the county of New York and State of New York, have invented a new, original, and ornamental Design for a Demonstration Booth, of which the following is a specification, reference being had to the accompanying drawing, forming part thereof.

In the drawing:

Fig. 1 is a front perspective view of a demonstration booth showing my new design; and

Fig. 2 is a rear perspective view with the top portion in a folded position.

I claim:

The ornamental design for a demonstration booth, as shown.

RENE D. WASSERMAN.
